UNITED STATES PATENT OFFICE

JAMES BOWEN, OF SWANSEA, WALES

MEANS FOR AIR COOLING THE CYLINDERS OF INTERNAL-COMBUSTION ENGINES

Application filed August 8, 1928, Serial No. 298,324, and in Great Britain August 23, 1927.

The invention relates to means for air cooling the engines of internal combustion engines, which provide for setting up a forced air current over the cylinder or cylinders of the engine, to assist in cooling said engine, and which include a thermostat-controlled valve in the passage of said air current for regulating or controlling, automatically, the said current so as to vary same according to the temperature of the engine, and so retain said engine, at as far as possible, a uniform and most efficient temperature at all engine speeds and loads.

The present invention is characterized by the employment of a thermostat element consisting of an elongated member constructed to bend under the influence of heat, fixed at one end and having its other end free, said free end being coupled to a control valve located in the air passage.

In carrying out the invention I prefer to employ an engine-driven pump, either a suction or a pressure producing pump, for creating the air current in the jacket, said pump serving either to extract the hot air from said jacket by suction or to force it therefrom out of suitable outlets by pressure as the case may be. A regulating valve of butterfly or other suitable form is furnished in the air passage between the pump and jacket, said valve forming part of the air current controlling or regulating means which latter includes also a thermostat element associated with the jacket, which is constructed to distort from a normal position by the effect of heat, the regulating valve being connected or coupled to a part of said element which becomes thus distorted, either directed or through the medium of suitable intermediate elements. The thermostat element preferably is in the form of a fluid-filled tube, accommodated in a suitable housing.

In order that the invention may be readily understood reference is directed to the accompanying drawings illustrating apparatus of practical form in accordance therewith, wherein

Figure 1 is a side view of said apparatus shown applied to a two-cylinder air-cooled engine,

Figure 2 is an end view of Figure 1, and

Figure 3 is a plan view of Figure 1,

Figure 4 is a sectional view of one of the cylinder-engaging jackets, and

Figure 5 is a plan view of one of the thermostat elements and the housing therefor.

Similar references indicate corresponding parts in the several views.

Over the upper part or head of each of the cylinders *a* of the engine is fitted a jacket 1 in the form of a cap in the top and side wall of which are formed a plurality of perforations 2, said jacket being held in position on the cylinder by means of retaining bolts 3 which extend from above the top of said jacket to below the cylinder cooling fins *b*, against the bottom edges of which latter bear nuts 4 which are screwed on to said bolts. Internally the jacket is cast with a plurality of air baffles or fins 5, so arranged, according to the arrangement of the engine cylinder fins, that they assume positions between said cylinder fins. In the example shown in the drawings the engine cylinders are shown as having vertical fins with the air baffles in the jacket fashioned to suit, but obviously the jacket could be constructed with horizontal baffles for use with a cylinder having horizontal fins.

The bottom of the cap 1 is formed with a flange 6 and below the said flange is fitted an annular channel-section housing 7 with the mouth of the channel uppermost, a fibre or other packing ring being interposed between the bottom of the cap 1 and said housing 7 to form a tight and heat-insulating joint. The housing 7 is formed with fixture lugs 9 through which pass fixing screws which screw into corresponding lugs or other suitable part of the cap 1, said screws serving to clamp the said housing to the cap. The bolt holes in the lugs 9 may have fibre bushes so as to prevent the conduction of heat via the bolts.

In the hollow of the housing 7 is accommodated a thermostat element 10 consisting of an arcuate closed metal tube, having a degree of flexibility, preferably of oval or elliptical section, which is filled with suitable fluid. The said tube is fixed at one end by a lug 11 or the equivalent to the housing 7, the remainder of said tube being capable of free

movement, and said tube is spring influenced or made of a material having inherent spring qualities, so that normally its free end assumes a position in fairly close proximity to the inner wall of the housing. The effect of heat is to cause expansion of the fluid within the tube, with the result that said tube tends to straighten and assume a larger diameter coil. The free end of said tube has connected to it a flexible cable 12, which passes out of the housing and has fixed to its other end a lug 13 which is pivotally connected to one limb 14 of a pivoted rocker. In the other limb 15 of said rocker is a slot 16 which is traversed by a pin 17 projecting from a disc 18 mounted on the spindle of a butterfly valve 19, the latter being mounted in and serving to regulate the current of air passing through a duct 20 which latter consists of an integral 20 radial extension of the cap 1. Thus the thermostat tube 10 serves to actuate the valve 19 through the medium of the cable 12, the rocker 14, 15 and the disc 18, the valve 19 normally being closed corresponding to the free 25 end of the tube 10 being in its innermost position.

To the ducts 20 are connected branches 21 from a manifold pipe 22, one end of said manifold pipe communicating via an intermediate pipe 23 with a suction pump 24 constantly driven by the engine, the said pump serving to extract the hot air from the manifold pipe and jackets when the valves 19 become opened. At the other end of the manifold pipe 22 is fitted a suitable relief valve 25 which is spring influenced and opens automatically to admit air from atmosphere into the pipe 22 and prevent too great a decrease in pressure in said pipe when the valves are shut, as for instance, when the engine is being started up from cold.

Any suitable fluid of suitable specific gravity may be used in the thermostat tube but a particularly suitable liquid which I may use for the purpose is methyl alcohol (CH_3OH , distillation of wood 98%).

Instead of producing a suction effect, the pump 24 may be a pressure-producing pump, in which case it delivers cool air to the manifold pipe 22 and to the jackets 1, and serves to discharge the hot air therefrom. In this case the valve 25 will be in the form of a safety valve to release undue pressure from the manifold pipe 22.

It will be followed that the apparatus above described will serve to retain the engine at a practically uniform predetermined temperature. Should said temperature exceed such predetermined degree the thermostat tube will tend to straighten, and in doing so, will open the valve to a greater extent. Should the engine temperature fall below such predetermined degree, the said tube will tend to assume a smaller coil, and in doing so will cause

the valve to close and reduce the air current passage.

If desired, the relief valve 25 also may be operated by the thermostat tube, or an auxiliary thermostat specially provided for this purpose. 70

Various constructional modifications may be made in the apparatus herein described, without departing from the scope of the invention. 75

What I claim is:—

1. An internal combustion engine having its cylinder provided with heat dissipating fins, a cooling device for the cylinder comprising a jacket having heat dissipating fins 80 therein for engagement between the fins of the cylinder when the jacket is engaged thereon, means engageable with the fins of the cylinder for retaining the jacket thereon, and means for creating suction in the jacket. 85

2. A cooling device for the cylinder of an internal combustion engine comprising a jacket for engagement on the cylinder and having an annular flange, an annular housing associated with the jacket, said housing having an open upper end closed by said flange, a valve associated with the jacket, means for creating suction in the jacket, and a heat responsive element confined in the housing for controlling the movement of the valve. 90

In testimony whereof I have hereunto signed my name. 95

JAMES BOWEN.
